UNITED STATES PATENT OFFICE.

HEWITT A. GEHRES, OF MOUNT VERNON, OHIO.

DRIVING MECHANISM FOR ENGINE ACCESSORIES.

Application filed August 2, 1922. Serial No. 579,107.

The invention relates to engines of the type employing rotary crank structures to transfer the reciprocatory motion of the pistons into rotary motion, and wherein the 5 rotary motion of such crank structure is utilized to drive accessory devices which are associated with the engine.

One object of the invention is to provide a driving mechanism of the above nature 10 which will enable the lay shaft or valve actuating shaft of the engine to be actuated by the movement of the crank structure.

Another object is to provide a crank-actuated driving mechanism which will be 15 self adjusting as regards accommodation to the various changes in position which may take place between the driving and the driven elements of such device.

The invention also aims to enable engine 20 accessories such as an indicator reducing motion, an oil pump, or both to be driven from the crank structure by a mechanism which will avoid as far as possible complicated parts or numerous elements, to the 25 end that such driving mechanism may be simple and direct in its action.

Further objects and advantages of the 30 invention will be in part obvious and in part specifically pointed out in the description hereinafter contained, which, taken in connection with the accompanying drawings, discloses a preferred embodiment thereof: such embodiment, however, is to be considered as merely illustrative of its principle.

35 In the drawings:

Fig. 1 is a plan view of a driving mechanism constructed in accordance with the invention, the cover of the housing for such mechanism being removed to expose its interior elements.

40 Fig. 2 is a side elevation of the apparatus shown in Fig. 1, certain of the parts at the crank pin end of the mechanism being shown in section.

45 Fig. 3 is a perspective view showing the driving mechanism in operative relation to the associated parts of the engine.

Fig. 4 is a sectional view taken on line 4-4 of Fig. 1 looking in the direction of the 50 arrows.

An important object of the present invention is to enable the valve-actuating shaft, or lay-shaft, of a gas engine or steam engine to be driven in proper timed relation to the cycle of the engine, by a mecha-

nism which will be as simple as possible and capable of being readily installed without involving extensive alterations of or additions to the fundamental structure of the engine.

In accordance with this invention, the motion of the crank structure is relied upon to drive the valve-actuating shaft, the illustrated embodiment of the invention being applied to an engine having a crank pin 1 60 mounted upon a throw arm 2, which parts and their associated engine structure will not be described in further detail, since they may be understood as of any suitable type.

The valves of the engine are actuated by 70 means of a shaft 3 which extends longitudinally from the cylinder structure of the engine (not illustrated) to the region of the crank structure; in the present embodiment this shaft 3 may be understood as constituting the lay-shaft itself the latter serving directly to operate the valves by actuating devices of any suitable type.

In order to rotate the shaft 3 from the 75 crank structure, I employ a crank structure 80 engaging member 4 which preferably is received within a recess 5 (Fig. 2) in the crank pin 1, the crank structure engaging member 4 being connected to a drag crank 6 which is provided with bearing means for guiding the same to turn about a centre substantially in line with the centre of rotation of the crank structure. The rotary movement of the crank 6 is then suitably transmitted to the shaft 3, preferably by means of a cross 85 shaft 7 disposed substantially in line with the centre of the circle of rotation of the crank structure, and driven by the drag crank 6; in the present instance engaging bevel gears 8 and 9 are mounted respectively 90 on the shafts 7 and 3 for the purpose of turning the latter.

The above described parts may be advantageously mounted within a housing 10 provided with inner and outer bearings 11 100 and 12 respectively, for the cross shaft 7, and a further bearing 13 for the valve-actuating shaft 3. The housing 10 also preferably is suitably secured to the adjacent portion 14 (Fig. 2) of the engine frame, thus 105 serving to fix the driving mechanism substantially in correct position with regard to the associated parts of the engine, when the housing 10 is secured in place. As shown, a cover 15 (Fig. 2) is associated with the hous- 110

ing 10 to provide a complete enclosure for the gears 8 and 9, and adjacent parts.

Since the crank 1 rotates in timed relation to the motion of the engine piston or pistons, the valve-actuating shaft 3 will be driven correctly by a mechanism of the above character, the gears 8 and 9 making it possible to obtain the desired speed ratio between the engine and shaft 3. Thus the shaft 3 will be operated by a driving mechanism which involves only the addition of a few simple parts to the fundamental engine structure.

The driving mechanism preferably is arranged to accommodate itself to relative endwise motion between the cross shaft 7 and the crank structure of the engine, such as might take place,—for example, if the rotation of the crank shaft should be accompanied by a slight back and forth motion, and to accomplish this, certain of the members 4, 6 and 7 previously described, are slidably mounted; in the present embodiment, the crank pin engaging member 4 is slidably received within a crank pin collar 16 (Fig. 2), and the drag crank 6 is fixedly secured to the inner end of cross shaft 7 as by means of bolts 17 extending between the drag crank and a flanged collar 18 secured to shaft 7. Thus any endwise motion between the crank structure and cross shaft 7 is taken up between the members 4 and 16, without imposing strains upon the driving mechanism.

The driving mechanism, furthermore, preferably is provided with a simple adjustment to compensate for other displacements which may take place between the crank structure and the cross shaft 7. As illustrated, the drag crank 6 is engaged with member 4 through the medium of a ball joint consisting of a socket member 19 (Fig. 2) associated with member 4 and provided with a cap 20, enclosing a ball 21 having a recess 22 which receives slidably the outer end of drag crank 6; thus, if crank pin 1 does not rotate in a circle truly concentric with shaft 7, the drag crank may slide in and out with regard to ball 21, the latter also acting to adjust itself automatically to any misalignment between the crank structure and shaft 7, by moving angularly relatively to the socket member 19. Although, in the present embodiment of the invention, the elements 20 and 21 of the joint above mentioned are of spherical shape, this shape is not essential, and the term "ball joint" is to be understood as not limited to spherical parts, but as embracing any joint which will permit a certain amount of angular motion as above described, between the crank 6 and the crank structure engaging member 4.

The driving mechanism also may be arranged to operate engine accessories, such as a force feed pump 23 (Fig. 3), an indi-

cator actuating device, and an auxiliary oil pump (not illustrated) for an oil reservoir associated with the engine frame beneath the crank structure.

In the present form of the invention, an eccentric 24 carrying a strap 25, is mounted upon cross shaft 7 between collar 18 and bearing 11, a bell crank lever 26 being pivoted at one end to the strap 25 and fixed at its other end to an indicator actuating spindle 27 suitably journaled in the housing 10, thus serving to oscillate spindle 27 in timed relation to the motion of the engine. As shown, an indicator drive arm is fixed to spindle 27, its upper end projecting into the space normally covered by the cap 29 (Fig. 2) mounted upon cover 15, whereby the arm 28 is rendered accessible by the removal of such cap. The remaining arm 30 of bell crank lever 26 may be connected to an actuating rod 31 (Fig. 2) for the oil pump above referred to, as located in the oil basin in the engine frame. The oil pump 23 may be driven from the eccentric 24 by means of an actuating rod 32 pivoted to the eccentric strap 25.

The driving mechanism also preferably is provided with means affording proper lubrication for its several parts, particularly at the crank pin end. In the present embodiment, the shaft 7 is hollow and is fed with oil at its outer end from the cap 33 (Fig. 2) having a duct 34 extending between the hollow of the shaft and a pipe 35 which conveys oil under pressure,—for example, from pump 23 previously mentioned. The oil passes through shaft 7 and into a conduit 36 in drag crank 6, thus conveying oil to the outer end of the drag crank where it lubricates the ball joint by means of ports 37 in the drag crank, and ports 38 in the ball 21. The crank pin engaging member 4 is also made hollow to provide a conduit 39 (Fig. 2) leading from the ball joint to the recess 5 in the crank pin, whereby the oil may lubricate the engaging surfaces of members 4 and 16, as well as the exterior surface of crank pin 1, by means of a duct 40 in the crank pin. As shown, the bearings 11 and 13 are lubricated by means of oil basins 41 and 42 respectively, the oil basin 42 also having an oil conveying trough 43 (Fig. 1) to carry oil scraped from the back of gears 8 and 9, to oil basin 42.

While a preferred embodiment of the invention has been described, it will be obvious that many changes may be made therein without departing from its principle, as defined in the appended claims.

I claim:

1. A driving mechanism for engine accessories, comprising a crank pin engaging member, a ball and socket joint associated with said member, a drag crank slidably connected to one element of said ball joint,

and a cross shaft substantially concentric with the circle of rotation of the crank pin, said cross shaft being fixedly connected to said drag crank.

5 2. The combination set forth in claim 1, wherein said crank pin engaging member is slidably engaged with the crank pin.

3. A driving mechanism for engine accessories, comprising a member slidably engaging the crank pin, a socket element carried

make up a ball and socket joint, a drag crank provided with bearing means positioning the same to rotate in a circle substantially concentric with the circle of rotation of 15 the crank pin, said drag crank being slidably connected with said ball element.

In testimony that I claim the foregoing, I have hereunto set my hand this 29th day of July, 1922.

HEWITT A. GEHRES.
